FOREST T. BARTON AND OSCAR HENSON, OF SEATTLE, WASHINGTON, ASSIGNEES
OF ONE-THIRD TO LEO N. KEMPER, OF SEATTLE, WASHINGTON.

GARMENT-EXHIBITING APPARATUS.

1,088,958.

Specification of Letters Patent. Patented Mar. 3, 1914.

Application filed March 31, 1913. Serial No. 757,798.

To all whom it may concern:

Be it known that we, FOREST T. BARTON and OSCAR HENSON, citizens of the United States, residing at Seattle, in the county of King and State of Washington, have invented certain new and useful Improvements in Garment-Exhibiting Apparatus, of which the following is a specification.

This invention relates to improvements in store-fixtures and particularly to devices for storing and exhibiting garments for sale.

The object of the invention is the provision of improved garment supporting apparatus within a containing-case and means to reciprocatively mount said apparatus to convey the garments thereon forwardly to the exterior of the case for inspection.

A further object of the invention is the provision of locking devices for said garment-supporting apparatus and a door of the case whereby neither said apparatus nor said door may be opened while the other is open or in any excepting its most rearward position.

25 The invention consists in the novel construction of garment supporting apparatus, the adaptation and combination of means of mounting the same within a show-case, and the combination therewith of said locking devices, as will be fully described in the following specification, illustrated in the accompanying drawings, and finally set forth in the appended claims.

In said drawings, Figure 1 is a top plan view of apparatus embodying our invention. Fig. 2 is a fragmentary vertical cross-sectional view through 2-2 of Fig. 1. Figs. 3 and 4 are fragmentary enlarged views of the locking devices. Fig. 5 is an enlarged cross-sectional view through 5-5 of Fig. 2.

Referring to said views, the reference numeral 1 indicates the rear-wall of a show-case adapted to retain and exhibit garments for sale.

45 2 indicates the respective end-walls and 3 and 4 the front and rear rails of the glass-paneled top of the case.

50 5 designates a door adapted, when opened, to slide in grooves 6 within the case in planes parallel to said end walls 2 and when closed to be slidably withdrawn for a distance and then swung laterally in grooves 7 into position, closing the front of the case, substantially as illustrated in our application for 55 patent, Serial No. 755,303.

The reference numeral 8 indicates a pair of parallel track-rails spaced apart at each end by metal strips 9 and fixedly secured thereby to the front and rear rails 3 and 4 of the top. Said track-rails are each formed 60 with upwardly curved ends 8¹ and a straight medial portion spaced below said top. A frame reciprocally mounted on said track rails consists in a pair of runners 10 rigidly connected together in spaced parallel relation by cross-braces 11. Each said runner is provided with a longitudinally arranged channel 12 adapted to receive said track-rails and is supported from said rails by means of a roller 13 rotatably mounted in 70 integral ears 14 intermediate the ends of the runner. A roller 15 is rotatably mounted between downwardly projecting ears 16 at the rear end of each runner and bears upon the underside of the respective track-rail. A 75 rod 17 is supported by the runners at their front ends extending rectangularly thereto for a suitable distance at each side within the case-compartment. Suit hangers, as 18, may be mounted on said rod 17 and garments 80 exhibited thereon arranged in close parallel order. As outlined said frame is reciprocally mounted on said track-rails 8 and the weight of the garments dependent from the rod 17 are borne upon the rollers 13 while 85 the rear rollers 15 facilitate the movement of the frame longitudinally of the track-rails. Usually the frame will be maintained in the position indicated in full lines in Fig. 1; that is to say, with the garment support- 90 ing rod 17 retracted within the case-compartment so that the doors may be closed. When it is desired to inspect the contents of the case, the frame is drawn outwardly by the operator exerting a pull upon the handle 19. 95 The frame and its load is then advanced to the positions indicated by dotted lines in Figs. 1 and 2 wherein the rod 17 is shown outside of the case and the garments supported thereby may be readily examined. 100 The frame may be drawn outwardly to any distance limited only by the interference of the rollers 13 with the forward curved ends 8¹ of the track-rails.

A latch is provided for the door and 105 frame consisting in a mandrel 20 mounted in bracket bearings 21 upon the rear wall 1 of the case. Rigidly secured at opposite ends of said mandrel are dogs 22 and 23 each formed in its lower edge with a hook 110

24. Between said hook and the extremity of the dogs they are each formed with a cam-edge 25 and are similarly formed with a cam-edge at 26 between said hook and the connection with the mandrel. Said mandrel is mounted to afford a limited oscillatory movement, the dogs at each end thereof normally occupying, through their gravity, a horizontal position, as indicated in full lines in Fig. 4.
- The door 5 is provided with a corner-plate 27 on which the guide-pin 28 of the door is mounted. Said plate is formed with an aperture having a lower edge 29 in line with said dog 23, said aperture communicating with a recess 30 provided in the door. An upward extension of said ears 16 is provided with a laterally projecting pin 31 in line with the dog 22.
- 20 Assuming that the door is open and latched, as indicated in full lines in Fig. 3, it will be noted that the dog 23 is entered into the recess 30 and the hook 24 thereof caught upon the plate at the lower edge 29 of its said aperture. Thus, when the frame is in its outward position, the door could not be drawn out and endanger the glass therein by accidentally clashing the same against the end of rod 17.
- 30 When the frame is pushed back into the case, the pin 31 may be engaged by the hook 24 of the dog 22. To permit the door to be closed, said frame is pushed farther rearwardly, bringing the pin 31 into contact with the cam-edge 26 and thereby oscillating the mandrel 20 and raising the dog 23 and freeing the door 5. The latter may then be closed but, meantime, the frame may not be drawn outwardly until the door is again 40 opened and the rearward movement of the door and contact of the lower edge 29 of its aperture with the cam-edge 24 of the dog 23 oscillates the mandrel 20 in turn to release the frame.
- 45 There may be a door provided at each side of the case, as indicated in Fig. 1 and each is provided with latching mechanism, as described, which is operative with devices upon the frame at each side thereof. Thus 50 when either door is in locked open condi-

tion, it may only be released conveniently by the rearward travel of the frame and it, in turn, may not be released except by the rearward movement of both doors at the farthest extremity of their travel.

55

The invention is simple of construction, strong and durable, with few parts to get out of order and may be made of unobtrusive and pleasing appearance as a fixture for stores of the higher grade.

60

While we have described our invention with some detail, we do not mean to confine ourselves to the precise construction shown, as obviously various changes and modifications in detail may be made within the scope 65 of the claims without departing from the spirit of the invention or sacrificing its advantages.

70

Having described our invention, what we claim, is—

1. In a show-case of the class described, the combination of a suitable case provided with a sliding door opening within the side of its compartment, a pair of track rails secured at the top of said compartment, garment supporting apparatus arranged to be reciprocatively mounted on said track-rails, means to lock said apparatus within the compartment, and means actuated by movement of said door to release the locking 80 mechanism of said apparatus.

75

2. In a show-case of the class described, the combination of a suitable case provided with a sliding door opening within the side of its compartment, a pair of track-rails secured at the top of said compartment, garment supporting apparatus arranged to be reciprocatively mounted on said track-rails, locking means for said apparatus and said door whereby both may be locked within 90 the compartment and either released by means of the other.

85

Signed at Seattle, Wash., this 13th day of March, 1913.

FOREST T. BARTON.
OSCAR HENSON.
